UNITED STATES PATENT OFFICE.

CYRUS S. DEAN, OF BUFFALO, NEW YORK, ASSIGNOR TO ALBERT D. JAMIESON, OF BUFFALO, NEW YORK.

ROTARY MOTOR OR TURBINE.

No. 838,088.

Specification of Letters Patent.

Patented Dec. 11, 1906.

Application filed July 14, 1905. Serial No. 269,693.

To all whom it may concern:

Be it known that I, CYRUS S. DEAN, a subject of the King of Great Britain, residing at Buffalo, county of Erie, and State of New York, have invented certain new and useful Improvements in Rotary Motors or Turbines, of which the following is a specification.

This invention relates to rotary motors or turbines.

10 It has been proposed heretofore to operate tube or flue cleaners or scrapers by compressed air, steam, or water and to direct the jet of motive fluid against a turbine or vane wheel at an angle to the general plane of the 15 wheel. This subjects the wheel to great sideways pressure and causes the wheel and its abutting parts to quickly wear out.

20 My object is to provide in the present invention a turbine or vane wheel having its vanes arranged transversely of the wheel at right angles thereto and to dispose the ducts or ports conveying the motive fluid in such manner that they discharge in the same plane as that of the turbine-wheel, whereby the 25 turbine-wheel is subjected to rotary action only and all end or side thrust entirely obviated, thus minimizing wear and obtaining the greatest rotative effect from the fluid-pressure.

30 Another object is the provision of an improved shell construction of few and simple parts, adapted for rapid and easy assembly and separation, and which provide the greatest possible space for the fluid-pressure.

35 The invention is set forth in detail herein-after, and the novel features are recited in the appended claims.

In the accompanying drawings, Figure 1 is 40 a side elevation of the invention shown within a tube or flue which is in section; Fig. 2, a longitudinal section, and Fig. 3, a cross-section on line 3-3 of Fig. 2.

An ordinary tube or flue of a steam-boiler is shown at 1, and the present invention is 45 tended to be inserted bodily within the flue or tube and fed therethrough by hand.

The shell or casing consists of a back part 2, a front part 3, and a central part 4, which latter is an annular band held between the 50 parts 2 and 3 by the bolts 5, which connect parts 2 and 3 together. The air, steam, or water hose 6 is coupled to the back part 2 and conveys the motive fluid to the device.

The back part 2 is hollow to permit the free passage of the motive fluid to the spaces 55 7, which lie between the entrant portion 8 of front part 3 and the central part or band 4, said spaces being provided by forming the part 8 of less size than part 4 and providing said part 8 with projections 9, which abut the 60 part 4 and have formed therethrough, preferably tangentially, ports or ducts 10 for delivering the motive fluid to the vanes 11 of the turbine-wheel 12. The vanes 11 extend transversely of the wheel 12 at right angles to 65 the plane thereof, but are dished or curved to better receive the motive fluid issuing from ducts 10. The ducts 10 extend substantially at right angles to the vanes 11—that is, they lie in the same plane with the turbine-wheel. 70 The entire force of the motive fluid is with this arrangement used solely to rotate the turbine-wheel, and no harmful end or side thrust is caused by the motive fluid, as in former constructions. 75

The turbine-wheel is loosely mounted on a stub-shaft 13, secured by a screw 14 in the long double boss 15, which is formed integral with the solid imperforate wall or web 16 of the part 8. 80

Interposed between the turbine-wheel and the boss 15 is a washer 17.

Loose on the shaft 13 and secured to the turbine-wheel by screws 18 is a cleaner-head 19. A nut 20, screwed on the end of shaft 13, 85 holds the head 19 and turbine-wheel loosely on the shaft 13.

As long as a motive fluid is supplied to the device the turbine-wheel and cleaner-head will be rotated at high rate, and as the cleaner 90 is pushed through the tube or flue by hand the cutters rotate slowly. The motive fluid exhausts directly from the turbine-wheel into the tube or flue.

Having thus described my invention, what 95 I claim as new, and desire to secure by Letters Patent, is—

1. In a rotary motor or turbine, the combination with an inner hollow shell or casing, of a separate outer hollow shell or casing surrounding the inner shell or casing and separated therefrom by a motive-fluid space, an annular member completely closing the outer end of the motive-fluid space between said inner and outer shells or casings, means 100 whereby the motive fluid may be introduced 105

only to the space between the said shells or casings, ducts leading through said hollow inner shell or casing from the motive-fluid space aforesaid to the interior of said inner shell or casing to let the motive fluid through, said ducts being forwardly inclined and lying substantially in the plane of the turbine-wheel, and a rotatably-mounted turbine-wheel having vanes located inside the inner shell or casing, said vanes being positioned to receive the motive fluid issuing from the ducts aforesaid, in a direction substantially at right angles to their surfaces.

2. In a rotary motor or turbine, the combination with an inner hollow shell or casing, of a separate outer hollow shell or casing surrounding the inner hollow shell or casing and separated therefrom by a plurality of motive-fluid pockets, an annular member completely closing the outer end of the motive-fluid space between said inner and outer shells or casings, means whereby the motive fluid may be introduced only to the space between the said shells or casings, ducts leading from the respective pockets aforesaid through said hollow inner shell or casing to the interior thereof to let the motive fluid through, said ducts being forwardly inclined and lying substantially in the plane of the turbine-wheel, and a rotatably-mounted turbine-wheel having vanes located inside the inner shell or casing, said vanes being positioned to receive the motive fluid issuing from the ducts aforesaid in a direction substantially at right angles to their surfaces.

3. In a rotary motor or turbine, the combination with an inner hollow shell or casing and a separate outer hollow shell or casing surrounding the inner shell or casing and separated therefrom by a motive-fluid space, one of said casings having an annular shoulder abutting the end of the other shell or casing and completely closing the outer end of the motive-fluid space between said inner and outer shells or casings, means whereby the motive fluid may be introduced only to the space between the said shells or casings, ducts leading through said hollow inner shell or casing from the motive-fluid space aforesaid to the interior of said inner shell or casing to let the motive fluid through, said ducts being forwardly inclined and lying substantially in the plane of the turbine-wheel, and a rotatably-mounted turbine-wheel having vanes located inside the inner shell or casing, said vanes being positioned to receive the motive fluid issuing from the ducts aforesaid in a direction substantially at right angles to their surfaces.

In testimony whereof I hereunto affix my signature in presence of two witnesses.

CYRUS S. DEAN.
